UNITED STATES PATENT OFFICE

138,196

DESIGN FOR AN ADJUSTABLE NURSING BOTTLE SUPPORT

Abraham Filler, New York, N. Y.

Application October 30, 1943, Serial No. 111,544

Term of patent 7 years

(Cl. D83—8)

To all whom it may concern:

Be it known that I, Abraham Filler, a citizen of the United States, residing at New York city, in the county of the Bronx and State of New York, have invented a new, original, and ornamental Design for an Adjustable Nursing Bottle Support, of which the following is a specification, reference being had to the accompanying drawing, forming a part thereof.

Fig. 1 is a side view slightly in perspective, of an adjustable nursing bottle support, showing my new design.

Fig. 2 is an end view of the adjustable nursing bottle support shown in Fig. 1, as viewed from the righthand side thereof.

The dominant features of the design reside in the portions shown in full lines.

I claim:

The ornamental design for an adjustable nursing bottle support, substantially as shown and described.

ABRAHAM FILLER.
